WINDOW CONSTRUCTION

Edmund Peremi, Manhasset, and Louis Toth,
Flushing, N. Y.

Application December 5, 1938, Serial No. 243,934

14 Claims.

(Cl. 189—72)

This invention relates to windows of the sliding or double hung type. One of the objects of the invention is to provide a frame and sash construction in which the frame has guide rails integral therewith for guiding the sashes, the sashes being provided with resilient sliding members adapted to slide on the guide rail portions of the frame and to seal the window against leakage and prevent rattling. The resilient engagement is such that while the windows at all times maintain a tight seal against the weather, the sashes slide freely without sticking or binding.

Other objects of the invention are to provide an improved construction for permitting the removal of sashes, improved means for securing the frames in the window opening of the building and an improved construction whereby the jamb members may be secured together to provide reinforced mullions, having space therein for reception of mullion reinforcing bars.

Another object of the invention is to provide an improved construction in which portions of the frame and portions of the sash cooperate to form recesses for counterbalancing means.

Other objects and advantages will appear from the following description of certain embodiments of the invention chosen to illustrate the principles thereof.

In the accompanying drawing:

Figure 1 is a vertical sectional view of a window having certain embodiments of the invention illustrated therein;

Figure 2 is a horizontal section of the window of Fig. 1 showing the cooperation between the sash and the frame;

Figure 3 is a horizontal section of the mullion of the window of Fig. 1;

Figure 4 is a perspective view partly in section showing the method of securing the bonding means to the frame;

Figure 5 is a horizontal section of sash and frame showing the method of removal of the sash;

Figure 6 is a horizontal section of a frame and sash of a modified construction.

Referring to the drawing in detail and particularly to Figs. 1 through 5 the window frame shown comprises jamb members 20, a header member 21, and a sill 22.

As illustrated in Fig. 2 the jamb 20 comprises a channel member which is bent upon itself at its edges to form inwardly and outwardly projecting beads 27 and 28 and to provide marginal flanges 23 and 24 which terminate in lips 25 and 55

26. The intermediate portion of the channel is bent towards the inside of the window opening to provide sash guide rails 30 connected by web 31. All of these parts are preferably formed of a single sheet of metal folded, drawn, or rolled to form. The metal used is preferably non-corrosive or non-ferrous, although this is not in all cases essential. The jamb member at the side of a window opening is preferably provided with means for bonding to the masonry such as corrugated strips 32. For engaging the corrugated strips with the jamb channel any suitable means may be used, but preferably the jamb channel adjacent to the offsets therein forming the sash guide rails is provided with notches 34. The bonding member 32 is provided at its inner end with tongues 35 and 36 adapted to interlock in the notches 34, and as illustrated particularly in Figs. 1, 2, and 4, one of the tongues 35 may be bent downward out of the plane of strip 32 and the other tongue 36 may be bent upward whereby a secure engagement between the strip and the frame is obtained.

The form of the jamb is such that where a multiple unit window is desired, two jamb channels may be placed back to back to form a mullion as shown in Fig. 3. The two jamb channels may be firmly secured together in any suitable manner, for instance by means of G-shaped clamping strips 37 of the form shown in our pending application Serial No. 238,352, filed November 2, 1938, these clamps being held in place by means of screws 38 or in any suitable manner and preferably containing a packing 39 for tightly sealing the space between the jamb channels. Where the window opening is large, reinforcement of the mullion is sometimes desired. This may be accomplished by providing metal bars fitting the spaces between the backs of the jamb channels. For instance a metal bar 40 may be placed between the backs of webs 31 and if needed additional reinforcing bars 41 may be fitted inside of the hollow sash guiding rails.

The sash stiles are of channel shape and include a base 45 carrying glass receiving means and being provided with an inside flange 46 terminating in an overhanging lip 47 and an outside flange 48 terminating in a lip 49. A resilient sealing and guide member is mounted in the sash stile channel and is shown as comprising a stepped base portion 50 lying in the bottom of the sash rail channel the base portion having at one edge a resilient tongue 52 adapted to engage the edge of the sash guide rail and having at its other edge a flange 54 which terminates

in a reentrant resilient tongue 56 adapted to bear against the side of the sash guide rail.

The flange 46 of the sash stile carries a laterally projecting flange 60 which extends fairly close to the lip 25 so as to nearly fill the space between the edge of such lip and the stile of the sash. When the sash is removed, sufficient space is left between the edge of the lip 25 and the sash guide rail 30 to permit access to the counterbalancing means 65.

The construction of the sash and jamb in this form of the invention is such as to permit removal of the sash, although no part of the jamb channel or sash guiding rails can be displaced. The removal of the sash may be accomplished by endwise removal of the resilient guiding and sealing member contained in one of the sash stile channels, or preferably the resilient guide and sealing members are so formed as to permit sufficient lateral displacement of the sash in the plane of the window as illustrated in Fig. 5 to allow the sash stile at the opposite side of the sash to clear its sash guiding rail so that such sash stile may be swung inwardly permitting the sash to be removed without removal of any part of the frame or detachment of one part of the sash from another.

The header member 21 shown in Fig. 1 comprises a metal member which may be formed of non-corrosive or non-ferrous metal if desired, and which is bent to provide a parting strip 70 and an outside flange 71, preferably terminating in a beaded edge 72. In the channel between the parting strip and the flange a bead 73 is formed. The top rail 74 of the sash is provided with an inner flange 75 terminating in a lip 76 and with an outer flange 77 which carries a lug 78. Retained by the lug 78 and the lip 76 is a resilient metal sealing member 80 adapted to contact with the bead 73 to seal the head of the sash. The ends of the flanges 75 and 77 are adapted to contact with the member 21 at each side of the bead 73 so that a three point seal is provided. The header member 21 may be reinforced by means of an angle member 81 which also serves for engagement with the masonry or for attachment to a lintel 83.

The sill member 22 shown in Figure 1 comprises an apron portion 90 having an outside flange 91 which terminates in an offset portion 92 for receiving caulking material 93. The sill is provided with an angular shoulder 94 adapted to be engaged by a resilient sealing strip 95 mounted in the recess of the lower sash rail 96. Inwardly of the sash the sill is provided with an upwardly bent flange 97 from which is bent a horizontal flange 98 terminating in an upwardly projecting lip 99. A sill reinforcing channel 100 is secured to the flange 98 and projects downwardly where it may be supported upon the masonry.

Figure 6 illustrates another modified form of window embodying our invention. In the construction here shown the jamb and sash guiding ribs are of the same form as shown in Figures 1 through 4 and need not be again described. The sash stiles are of channeled form and comprise a glass carrying base 140 carrying an inner flange 141 and an outer flange 143 terminating in a lip 144. Near the bottom of the channel in the sash stile formed by these flanges, a pair of lugs 135 and 136 respectively are provided. A resilient sealing and guiding member, formed of stainless steel, bronze or other resilient metal, is mounted in each sash stile channel and retained in

position by these lugs. In the form shown in Fig. 6 the resilient member comprises a base 150 resting on the bottom of the channel and carrying at one edge a resilient tongue 151 adapted to bear against the inner face of the sash guide. The base 150 carries at its other edge an outwardly projecting resilient tongue 152 which bears against the inner side of the sash guiding rib 118, and serves to draw the sash inwardly so as to hold the lip 144 in contact with the outer face of the sash guide rib. A three-point sealing engagement is thus secured between the sash and sash guide rib, which effectively seals the sash against the weather, while at the same time permitting some yielding movement of the sash both in the plane of the glass and at right angles thereto, so that the sash may be described as a floating sash which will slide freely at all times without sticking, jamming or rattling.

As described in connection with Figs. 1 to 4, the sash stile carries a laterally projecting flange 60 which extends fairly close to the lip 25.

While we have illustrated and described in detail certain preferred forms of our invention, it is to be understood that changes may be made therein and the invention embodied in other structures. We do not, therefore, desire to limit ourselves to the specific construction illustrated, but intend to cover our invention broadly in whatever form its principle may be utilized.

We claim:

1. In a window construction, a frame including a jamb member having sash guide rails, notches in said rails, and a bonding member for securing said frame to a building wall, comprising a portion of sheet metal extending from said frame, tongues on the inner end of said bonding member, said bonding member being secured to said jamb by insertion of said tongues into said notches.

2. In a window construction a frame including a jamb member having a pair of sash guide rails, a web joining said rails, and notches in the outer sides of said guide rails adjacent their outer ends, and a bonding member for securing said frame to a building wall, said bonding member comprising a portion of sheet metal extending from said frame into the building wall, said member being secured to said frame by tongues situated on the inner end of said bonding member, said tongues being inserted in said notches.

3. In a window construction, a frame including a jamb member having spaced sash guide rails and portions extending outwardly of said spaced guide rails, marginal flanges extending from said outwardly extending portions terminating in inwardly turned lips and sashes including channel shaped sash stiles engaged by said sash guide rails, flanges extending outwardly from said rails forming with said inwardly turned lips, said marginal flanges, and said outwardly extending portions of said jamb, counterbalance receiving pockets.

4. In a double hung window, a sash including a stile, said stile having a stepped base portion, a flange extending from one edge of said base terminating in an inwardly turned lip and a flange extending from the other edge of said base terminating in an inwardly turned undercut lip and a resilient metallic weather strip secured in said stile, the base of said strip being engaged by said stepped base, said strip having a resilient tongue extending inwardly from one side thereof and a flange extending from the other side of said base engaging the inner side of the latter mentioned

flange of the stile, said weather strip flange terminating in a reentrant resilient tongue, the angle between said weather strip flange and said tongue being engaged under said undercut lip.

5. In double hung window construction, a frame including a jamb having a sash guide rail thereon, and a sash including a channeled shaped stile, a resilient metallic weather stripping member imprisoned in said stile, said member having two flexible tongues engaging two sides of said guide rail at points intermediate the edges of said tongues, said edges being guarded from unlimited free movement when disengaged from said rail, the third side of said guide rail being engaged by a portion of said stile, said tongues being sufficiently flexible to provide for removal of the sash by lateral movement thereof in one direction whereby the channeled stile which engages the guide rail at the opposite side of the sash will disengage said rail and the sash can thereby be 20 moved outwardly of the window frame.

6. A mullion comprising two jamb members placed back to back, said jamb members including spaced hollow sash guide ribs and supporting bars situated in the hollow portions of said guide ribs.

7. A mullion comprising two jamb members placed back to back, said jamb members including folded beads on either edge thereof, said beads terminating in flanges, said jamb members including integral spaced sash guide rails intermediate said flanges, and a channeled clamping strip enclosing said folded beads for the full extent of the mullion and secured to said beads.

8. A mullion as claimed in claim 7 in which the space between said jamb members forms the shape of an H and reinforcing members filling the web and legs of said space.

9. In window construction including a frame having a header, said header having a bead thereon, a top sash rail, means on said top sash rail to provide three point contact with said header, including an inner flange on said rail having an overturned lip on the end thereof adapted to engage said header, an outer flange engaging said header, a lug on said outer flange, and a V-shaped metallic weather stripping member, the vertex of the V being held under said lug, and one leg of the V being a resilient tongue adapted to engage said bead on said header when said sash is closed whereby a three point contact is provided when said sash is in closed position said tongue being limited in upward movement when sash is open by said inwardly turned lip of inner rail flange.

10. In a window construction a frame including a sill having an apron portion terminating at its outer end in a downwardly extending flange, said flange having an inwardly turned portion at the end thereof terminating in a downwardly extending flange, said portion and said flange forming a caulking pocket accessible from the outside of the window, said sill having an angle shoulder situated inwardly of said apron adapted

5 to engage with a sliding sash, said sill having an upwardly bent flange inwardly of said shoulder having inwardly bent portion and a sill reinforcing channel secured to said inwardly bent portion, the lower side wall of said channel being adapted to engage the building wall and aid in supporting the sill.

11. In double hung window construction, jamb members having guides, inner and outer sashes having stiles, said stiles including base portions, pane receiving means on one side of said base portions and jamb engaging means on the other side thereof, said jamb engaging means including spaced flanges extending laterally in planes substantially parallel to the plane of the window and flanges extending outwardly of said stiles from the inner lateral flange of said inner stile and from the outer lateral flange of said outer stile respectively, said flanges forming counter-balance pockets with portions of said jamb members and said guides.

12. A window construction including a sash having upper, lower and side sash stiles, said upper sash stile having an inner upwardly extending flange terminating in an outwardly extending lip and an outer upwardly extending flange of substantially the same height as the inner upwardly extending flange, said outer upwardly extending flange having an inwardly extending lug situated thereon below the upper extremity of said flange and a resilient V shaped metallic weather strip entrapped therein, one leg of the V lying between said flanges and the other leg of the V held from unlimited movement by said lip.

13. In a window sash, a stile including a base portion and frame cooperating means, said means including a flange on one edge of said base and a shorter flange on the other edge of said base terminating in an inwardly turned lip, lugs on the inner sides of said flanges at a distance from said base, and a resilient window stripping member having a base portion, engaging said base of said stile, a reversely bent resilient flexible tongue extending from one edge of said base toward the other edge thereof, and an outwardly projecting resilient flexible tongue extending from the other edge of said base, said tongues being engaged by and held from unlimited movement by said lugs.

14. In a window construction, a frame including a sill, and a sash having a bottom rail, said bottom rail of said sash including a short inside downwardly extending flange and a longer outside downwardly extending flange, said sill including a substantial horizontal rail engaging portion engaged by said short inside flange when said rail is in closed position, said horizontal flange extending inwardly of the rail for a substantial distance when said sash is in closed position and then upwardly to form a pocket for condensed moisture.
